UNITED STATES PATENT OFFICE.

ARTHUR DESROCHERS, OF THETFORD MINES, QUEBEC, CANADA.

RAILWAY SWITCH.

1,411,844.

Specification of Letters Patent.

Patented Apr. 4, 1922.

Application filed January 4, 1922. Serial No. 526,907.

To all whom it may concern:

Be it known that I, ARTHUR DESROCHERS, a subject of the King of Great Britain, residing at Thetford Mines, Province of Quebec, Canada, have invented certain new and useful Improvements in Railway Switches; and I do hereby declare that the following is a full, clear, and exact description of the invention, such as will enable others skilled in the art to which it appertains to make and use the same.

This invention relates to improvements in automatic switch operating apparatus, having for an object to provide means for selectively operating the movable element or frog of a switch from a tramway car, train, or other rolling stock traversing a predetermined course, whereby a motor-man or other operator of the same can, by setting mechanism, conveniently operable from the rolling stock, cause the switch element to be thrown in that direction desired prior to the entrance of such rolling stock thereinto, and without the necessity of interrupting the same in its movement either before or after entering.

It is also an object of the invention to provide the apparatus with a novel form of controlling means, settable in a manner such as will insure proper operation of the switch and being operable either automatically or manually to release such settable means subsequently to the throwing of the switch element to the position desired.

Other objects will be in part obvious and in part pointed out hereinafter.

In order that the invention and its mode of operation may be readily understood by persons skilled in the art, I have in the accompanying illustrative drawings and in the detailed following description based thereon set out one possible embodiment of the same.

In these drawings:

Figure 1 is a perspective view of a tramway or a switch provided with the invention, a portion of the car being broken away to show the arrangement of the operating mechanism therein;

Figure 2 is a schematic view showing the relative arrangement of the active elements of the invention, such elements being illustrated in section, and the electrical circuits involving such elements;

Figure 3 is a vertical longitudinal section through the selective operating mechanism;

Figure 4 is a vertical transverse section through the above mechanism;

Figure 5 is an enlarged vertical transverse section through the selective operating mechanism showing the arrangement of the electro-magnetic and manual release means in closed position;

Figure 6 is a similar view showing the mechanism in open position;

Figure 7 is an enlarged fragmentary longitudinal section showing the connection of the settable means with the release mechanism;

Figure 8 is a horizontal section through the operating mechanism;

Figure 9 is a fragmentary detail in elevation of the particular form of trolley wheel and contact rollers employed; and,

Figure 10 is a vertical longitudinal section through the trolley wire contacts.

Having more particular reference to the drawings, in connection with which like characters of reference will designate corresponding parts throughout, 1 represents a tramway car of the electrical propelled type movable over an ordinary track 2 provided with a switch indicated in its entirety by the numeral 3 including therein a pivotal switch element or frog 4, which, as will be understood, by being shifted to either of its several positions, will cause the car 1 to correspondingly traverse the curves leading from the switch or main track 2. The tramway car 1 is supplied with the necessary energy from an overhead trolley wire 5 through the usual trolley pole 6 having a peripherally grooved wheel 7 rotatably mounted in bearings upon its upper extremity and contacting with said trolley wire 5 upon movement of the car.

With a view towards providing means for effecting pivotal movement of the switch element 4 to either one of its positions with respect to the switch 3, I arrange upon the opposite sides of said element metal or similar waterproof housings 8 and arrange in these housings electro-magnets 9 and 10, the cores of which are connected to the opposite sides of the free portion of the switch element, as shown in the Figure 2.

Arranged at one or either of the ends of the car 1 is a selective operating mechanism

adapted to selectively energize either the electro-magnet 9 or the electro-magnet 10, whereby to impart corresponding shifting movement of the switch element 4, such mechanism including a housing 11 having an intermediate horizontal partition wall 12 therein, while yieldable or spring cushioned contacts 13 and 14 are arranged on the bottom of said housing and connected to terminal posts 15, which, in turn, are provided with suitable means for facilitating the securing of electrical conductors to the same, as at 16. A plurality of plungers, three in number, indicated respectively by the numerals 17, 18 and 19, are slidably received through openings in the top wall of the housing 11, and the plungers 17 and 19 have their inner portions formed substantially square in cross section and slidably engaged through correspondingly shaped openings in the horizontal partition wall 12, the lower portions of said plungers carrying insulating blocks 20 on which contacts 21 and 22 are fixedly arranged, said latter contacts being provided with means for facilitating the securing of certain other electrical conductors thereto. Laterally inwardly extending arms 23 are fixedly arranged upon those portions of the plungers 17 and 19 just inside of the housing 11, and in order that said plungers will be normally retained in their uppermost positions, expansible coil springs 24 are arranged about their respective squared portions, certain of the ends of the springs having bearing upon adjacent portions of the arms 23, while the remaining ends bear upon adjacent portions of the partition wall 12. It will thus be obvious that by depressing either the plunger 17 or the plunger 19, the contacts 21 or 22 respectively carried thereon will be caused to engage the oppositely disposed spring cushioned contacts 13 and 14, and, in this way, close the electrical circuit through that particular portion of the operating mechanism which may be aptly referred to as the settable means.

A solenoid 25 is supported upon the lower side of the partition wall 12, intermediate the contacts 21 and 22, and has the armature or core 26 thereof slidably mounted in an elongated casing 27 about which the solenoid winding is coiled. A substantial bell crank lever or trip 28 is pivotally supported, as at 29, upon the upper side of the wall 12 in proximity to the open upper end of the casing 27 and has a dependent nib 30 formed on one end thereof adapted to be normally arranged in the open upper end of the casing 27, as shown in the Figure 5, while the free portion of said trip 28 is bifurcated and embraces the lower portion of the plunger 18. The plunger 18, in turn, has a tapered or frusto-conical shoulder 31 formed upon its intermediate portion adapted to contact with the bevelled inner sides of spring

pressed catches 32 pivoted upon either side of said plunger, as at 33, and supported upon an adjacent portion of the partition wall 12. A second annular shoulder 34 is formed upon the lower portion of the plunger 18, and serves for a purpose which will be hereinafter more fully described. Due to the tension applied to the pivotal catches 32, it will be understood that they will normally be moved into engagement with the adjacent surfaces of the frusto-conical shoulder 31.

The arrangement of the spring pressed pivotal catches 32 is such as will permit of the movement of the inner or free ends of the arms 23 over their bevelled inner sides and to engage with the undersides thereof, as shown in the Figure 8, whereby when said arms are so engaged with the catches, their respective plungers 17 and 19 will be temporarily retained in depressed positions.

Coming now to the means for conducting electrical current to the contacts 13, 21, 14 and 22 and the solenoid winding 25, the shaft upon which the trolley wheel 7 is mounted has its opposite portions extended and rotatably receives on these extended portions contact rollers 35, locking nuts 36 being turned into engagement with the extremities of these extended portions for an obvious purpose. Electrical conductors 37 and 38 are extended from the several contact rollers 35, while upon the trolley wheel 7 a main feed conductor 39 is extended, this latter conductor, as will be understood, supplying power to the motor of the car 1. The opposite ends of the conductors 37 and 38 are connected to the contacts 22 and 21 respectively, while a shunt conductor 40 is extended from the feed conductor 39 into engagement with the winding of the solenoid 25, from whence it is extended by way of a conductor 41 through a branch conductor 42 into engagement with the terminal post 15.

In order that electrical energy may be supplied to the electro-magnets 9 and 10 for selectively throwing the switch element 4, I provide a trip type of circuit closing device, arranging the same in a housing 43 which is supported between cables 44 secured to poles 45 arranged upon the roadway bordering the track 2. The lower side of this housing 43 is open, and to the underside of the top wall thereof, I secure a pair of rods 46 through the medium of brackets 47, arranging coil springs 48 upon said rods and permitting the same to bear, at their adjacent ends, upon trip arms 49 and 50, which trip arms, as will be noted, are pivotally supported upon longitudinal bars 51 disposed parallel of the housing 43 and secured at their opposite ends, in a suitable manner, thereto. A contact arm 52 is also arranged longitudinally of the housing 43, being secured at its opposite end to ad-

5 jacent portions thereof, and is grooved whereby to permit the same to have positive contact with an adjacent portion of the trolley wire 5. Electrical conductors 53 and 54 are connected to certain of the ends of the rods 46 and are extended into engagement with the terminals of the electro-magnets 9 and 10 respectively, the remaining terminals of these magnets being grounded 10 to the switch 3 through the medium of ground wires 55. Obviously, with energization of the magnet 9, the switch element 4 will be caused to move in a direction towards one particular core, while with energization of the electro-magnet 10, the switch element 4 will be caused to move in an opposite direction, thereby permitting of its selective operation for causing the tramway car 1 to traverse either of the curves of 15 20 the switch, that may be desired.

The operation of the invention may be reviewed as follows:

The motor-man of the tramway car 1 upon approaching the switch 3 in the track 2, 25 will, for purposes of illustration, depress the plunger 17, causing engagement between the contacts 21 and 13 and also engaging the arm 23 thereon with the spring pressed pivotal catches 32, thus holding the plunger 30 in its depressed position and the conductors 21 and 13 engaged. When that particular contact roller 35 carried upon the trolley wheel shaft extension engages the contact 35 40 45 50 55 60 65 70 75 80 85 90 95 100 105 110 115 120 125 130 arm 23, it will immediately complete an electrical circuit through the interengaged contacts 21, the arm 49 and the electro-magnet 9 connected thereto, the current going to ground by way of the ground wires 55. Because of this, the electro-magnet 9 will be energized and in consequence, will attract the pivoted switch element 4 thereto, closing the circuit accordingly. Simultaneously with energization of the magnet 9 for a period sufficient to attract the pivoted switch element 4, the electro-magnet 25 will be energized and will cause abrupt upward movement of its core 26 in the casing 27, therefor, whereupon said core 26 will impart a sharp or hammer like blow to the nib 30 carried on the adjacent end of the trip lever 28, thus moving the free portion of said trip lever downwardly so that it engages the annular shoulder 34 and pulls the plunger rod 18 downwardly, moving the frusto-conical shoulder 31 over the adjacent bevelled surfaces of the pivotal catches 32 and spreading the same sufficiently so as to cause disengagement between the particular catch 32 engaging the arm 23 of the plunger 17. At this time, the plunger 17 will immediately return to its uppermost position in the housing 11 under influence of the coil spring 24. Operation of the apparatus to effect movement of the switch element 4 in an opposite direction is identical with that above ex-

plained with the exception, of course, that the plunger 19, in this event, would be depressed and circuit would be closed upon engagement of the contact roller receiving the conductor 37 contacting with the pivoted 70 arm 50. Due to the pivotal spring mounting of the contact arms 49 and 50, it will be understood that the same will provide a brushing or wiping contact as between the rods 46 and the conductors 37 and 38, the 75 period of time consumed thereby being sufficient to permit of energization of the active elements of the invention. Should the motor-man, by mistake, depress either of the plungers 17 or 19, they may be immediately 80 released by manually depressing the plunger 18, causing the frusto-conical shoulder 31 to spread the catches 32 and thereby release the arm 23 of the erroneously depressed plunger 17 or 19, thus avoiding the necessity of having a tramway car enter the switch in the wrong direction.

Manifestly, the construction shown is capable of considerable modification and such modification as is within the scope of my 90 claims, I consider within the spirit of my invention.

Having thus fully described the invention, what I claim as new and desire to protect by Letters Patent is:—

1. Automatic switch operating apparatus, comprising in combination with electrically propelled rolling stock movable over the switch, electro-magnetic means for moving the switch element to its several positions, means operable from the rolling stock for selectively controlling the energization of the electro-magnetic means, means for temporarily securing said controlling means in their circuit closing positions, circuit closing means connected to the energy supplying conductor for the rolling stock adapted to be connected to the electro-magnetic means through the selectively controlled means, and means operable upon connection of said circuit closing means with the selective controlled means for returning the same to their normal position and deenergizing the electro-magnetic means.

2. Automatic switch operating apparatus, comprising in combination with electrically propelled rolling stock movable over the switch, electro-magnetic means for moving the switch element to its several positions, means operable from the rolling stock for selectively controlling the energization of said electro-magnetic means, automatically and manually operable means for retaining the selected controlling means in an operative position, said controlling means being electrically connected to the trolley of the rolling stock, and circuit closing means adapted to be engaged by said trolley connected to the electro-magnetic means for

establishing an electrical circuit through certain of the same dependent upon the selected controlling means, said selected controlling means being released from its operative position immediately subsequent to the energization of the electro-magnetic means.

3. Automatic switch operating apparatus, comprising in combination with the electrically propelled rolling stock movable over the switch, electro-magnetic means for selectively moving the switch to either of its several positions, circuit closing means adjacent the energy supplying conductor of the rolling stock individually connected to the electro-magnetic means, controlling means connected to the controlling contact of the rolling stock and comprising interengageable contacts, said interengageable contacts being included in individual electrical circuits including the trolley contact, and means for retaining certain of the interengageable contacts in their operative position, at times, but releasing the same with energization of the electro-magnetic means.

4. Automatic switch operating apparatus, comprising in combination with electrically propelled rolling stock movable over the switch, electro-magnetic means for selectively moving the switch to its several positions, individual circuit closing means connected to the trolley wire of the rolling stock and to the electro-magnetic means, controlling means for selectively energizing the electro-magnetic means electrically connected to the trolley wheel of the rolling stock, said trolley wheel having a pair of contacts thereon engageable, individually, with the circuit closing means, said controlling means including spring cushioned contacts, oppositely disposed depressible contacts adapted to engage with the adjacent spring cushioned contacts for completing electrical circuit therethrough, means for retaining either of said depressible contacts in its depressed position, means for effecting the manual release of said depressed contact, and other means for effecting automatic release of said depressed contact im-

mediately subsequent to the energization of 50 the selected electro-magnetic means.

5. Automatic switch operating apparatus, comprising in combination with electrically propelled rolling stock movable over the switch, electro-magnetic means for selectively moving the switch to its several positions, and controlling means for permitting of selective energization of the electro-magnetic means, comprising a housing having a horizontally partitioned wall 60 therein, spring cushioned contacts arranged in the bottom wall of said housing, depressible contacts extending from the top wall and partition wall of said housing, spring means for normally retaining said 65 depressible contacts in their inoperative positions, said depressible contacts being adapted to be engaged with the oppositely disposed spring cushioned contacts whereby to close an electrical circuit therethrough for 70 individually energizing the electro-magnetic means, laterally extending arms carried on the depressible contacts, spring actuated pivotal catches supported upon the horizontal partition wall and adapted to be engaged 75 by said lateral arms, manually operable means for moving said pivotal catches to positions whereat they will disengage the laterally extended arms, an electro-magnet positioned in proximity to said pivotal 80 catches having a movable core, a trip lever pivoted in proximity to the upper end of said last mentioned electro-magnet, and adapted to be actuated by said movable core of the same, whereby to automatically 85 operate said means for moving the pivotal catches to their released positions, the last mentioned electro-magnet being connected to and adapted to be included in either of the electrical circuits established through 90 the depressible contacts whereby to effect operation of its movable core immediately subsequent to the energization of the first electro-magnetic means.

In witness whereof I have hereunto set 95 my hand.

ARTHUR DESROCHERS.
